CLAIM

The ornamental design for an illuminated ice cream cone ornament, as shown and described.

DESCRIPTION

FIG. 1 is a top-front-left perspective view of an illuminated ice cream cone ornament showing my new design;

FIG. 2 is a bottom-rear-right perspective view thereof;

FIG. 3 is a front elevational view thereof;

FIG. 4 is a left-side elevational view thereof;

FIG. 5 is a detail view of area 5 of FIG. 4;

FIG. 6 is a front elevational view of the present invention having an illuminated first region showing the new design, wherein a second region is not illuminated; and,

FIG. 7 is a front elevational view thereof showing the illuminated second region, wherein the first region is not illuminated.

The dashed line showing an exemplary notebook and raised button in FIG. 1 through 7 is included for the purpose of illustrating environmental structure and forms no part of the claimed design. Further, the broken lines radiating from the cup rim in FIGS. 6 and 7 indicate illumination only and form no part of the claimed design. The dark shading in FIGS. 6 and 7 compared to the same region shown unshaded in FIGS. 1 through 5 indicates a contrast in appearance between unlit and lit regions, and does not depict any particular color, texture, or material.

1 Claim, 7 Drawing Sheets
